US0D1057408S

(12) United States Design Patent (10) Patent No.: US D1,057,408 S
(45) Date of Patent: * Jan. 14, 2025

(54) HANDBAG

(71) Applicant: Bottega Veneta S.R.L., Montebello Vicentino (IT)
(72) Inventor: Matthieu Blazy, Milan (IT)
(73) Assignee: BOTTEGA VENETA S.R.L., Montebello Vicentino (IT)

() Term: 15 Years

(21) Appl. No.: 29/904,303

(22) Filed: Oct. 4, 2023

(30) Foreign Application Priority Data

May 18, 2023 (EM) 015021788-0004
(51) LOC (15) Cl. 03-01
(52) U.S. Cl.
USPC D3/232
